UNITED STATES PATENT OFFICE.

FRANCIS M. SIMS, OF MANCHESTER, ASSIGNOR TO MORITZ BLUMANN, OF LONDON, ENGLAND.

LAMP FOR BURNING HEAVY HYDROCARBON OILS.

SPECIFICATION forming part of Letters Patent No. 441,446, dated November 25, 1890.

Application filed September 3, 1889. Serial No. 322,890. (No model.) Patented in England July 3, 1889, No. 10,724.

To all whom it may concern:

Be it known that I, FRANCIS MONTAGUE SIMS, a subject of the Queen of Great Britain and Ireland, residing at Manchester, in the 5 county of Lancaster, England, have invented Improvements in Lamps for Burning Heavy Hydrocarbon Oils, which improvements are also applicable to other purposes wherein it is desirable to maintain a fluid at a constant 10 level, (for which I have obtained Letters Patent in Great Britain, No. 10,724, dated July 3, 1889,) of which the following is a specification.

This invention relates especially to appliances designed for burning heavy hydrocarbon oils—such, for example, as those found in the Russian Empire, in the Province of Burmah, and elsewhere—the specific gravity of which is such that they cannot be burned 15 in ordinary lamps employed for burning the lighter kinds of hydrocarbon oils, as the capillary attraction is too weak to cause them to “ascend the wick,” and for this reason their use has hitherto been confined principally to 20 lubricating purposes. In burning oils of this class, beyond the question of the form of burner and the regulation of the draft, the primary requisite (as the heavy oil will not ascend the wick, excepting for a very short 25 distance by capillary attraction) is to provide means whereby the level of the oil in the burner can be automatically maintained at a point perfectly constant, or as nearly so as possible, and this level must be only a short 30 distance below the burning portion of the wick, so that the capillarity of the wick may be practically a constant force, in order that the wick shall be kept at all times sufficiently supplied with oil, at the same time that there 35 shall be no danger of the “flooding” or overflowing of the oil. The maintaining of the oil in the wick-holder at a constant level is a most important feature, because any variations of the level of the oil in the burner will 40 cause corresponding fluctuations in the light, as will be well understood by any competent person.

In the accompanying drawings, Figure 1 illustrates the general arrangement by which 45 I propose to effect the desired result, the oil-

reservoir being shown in section. Figs. 2, 2^a, 3, and 4 are detached sectional elevations of various modifications of the overflow-chamber D, hereinafter more particularly referred to.

55

A is an oil-reservoir, which is air-tight and is placed at some distance above the level of the burner B.

60

C is the supply-pipe, which proceeds from the bottom of the reservoir.

As in this pneumatic system the air entering the reservoir to supply the place of the oil withdrawn therefrom (be the quantity small or great) is subject to the law applicable to air and gases, that the force with 65 which it seeks to expand is equal to the compressing force and, inversely, as to the space which it occupies, I have, in addition to keeping the oil at a constant level, to provide means for the absorption of an excess and 70 varying quantity of oil, due to the fact that the oil issuing from the reservoir is greater in bulk than the air which entered the reservoir, which would tend both to disturb the level and to cause an overflow.

75

In order to apply my improved principle to any existing pipes or gasoliers or other similar fittings, I may proceed either, first, by dividing the pipe C above the level of the burner B, or, second, by leaving the pipe uncut, if 80 preferred. In either case the lower portion of the supply-pipe is bent upward, and the wick-holder is attached to the end thereof. The former case (wherein I divide the pipe C above the level of the burner) is illustrated 85 by the detached section, Fig. 2, which is drawn to a larger scale. Inside the lower end of the pipe C, (below the cut,) I insert a short inner tube a, of tapering form, its upper end fitting air and liquid tight into the supply-pipe C 90 and its lower end or mouth tapering off to a smaller diameter and extending to a point corresponding with the point in the wick-holder B at which I desire to preserve a constant level. I then reconnect the divided portion of the pipe with or without the addition at this point of a stop-tap b. I then perforate the outer pipe, as at c, so that air is admitted freely between the two concentric pipes c and a and can reach the lower opening or mouth 100

of the inner tube a ; or in some cases I dispense with the perforation c in the outer tube and admit air at the point c , as shown in section at Fig. 3, the socket d acting as a cover 5 and preventing the ingress of dust or other extraneous matter; or, if preferred, I admit air at the point e . (See Fig. 3.) In case I do not desire to cut the supply-pipe, I surround it at this point (see Fig. 2^a) with a short piece 10 of tube a^x of a slightly larger diameter, making a liquid-tight joint at the bottom end and leave the upper end open to the atmosphere, having previously perforated the supply-pipe 15 at a point corresponding with the point in the wick and oil holder at which I desire to preserve the level. This arrangement is virtually the same as the above, with the exception that the feed-pipe c is in the one case the outer of two concentric tubes and in the other it is 20 the inner one of the two, and in both cases the level of the oil will be maintained approximately at the point which corresponds in one case with the lower orifice or mouth of the inner tube and in the other case with the 25 perforation of the supply-pipe. As soon as the level of the oil falls below the mouth of the inner tube a in the one case or of the perforation in the feed-pipe C in the other case air is admitted and passes in the form of bubbles 30 up the supply-pipe C into the upper part of the reservoir A , allowing a corresponding proportion of oil to descend and raise the level, so as to again close the mouth or perforation and stop further descent of 35 oil. Owing, however, to the causes above mentioned this level would not always remain absolutely constant, and it is necessary, therefore, to provide for fluctuations in the level due to any excessive issue of 40 oil which might at times cause overflow or flooding, and for this purpose I fit the pipe C or the wick-holder B with what I term an "overflow-chamber" D , Fig. 1, the diameter of the said chamber being greater than its 45 height and considerably larger than that of the space between the outer and inner tubes C and a , so that any rise of level which would be quite appreciable in that space (and consequently in the wick-holder) will, when spread 50 over this increased area, be reduced almost to nil. This overflow-chamber D is placed round the feed-pipe (in the first case above referred to) in such a position that the bottom of the chamber D stands level with the mouth of 55 the inner tube a , the outer tube C having been perforated at this point c^x to allow the oil access to the overflow-chamber D .

In case two or second construction the outer tube carries the overflow-chamber through 60 which it passes, both tubes being perforated at the same level at the bottom of the chamber to allow the oil access to the chamber, and the upper part of the outer tube being also perforated or left open for the admission 65 of air. The upper end of the said outer tube is covered to prevent ingress of the foreign matter. The action will then be as follows:

When the apparatus is in use, the excess of oil due to air-expansion instead of raising the oil level in the wick-holder B , and possibly flooding, will be received into this overflow-chamber D , where it will be spread over the much greater superficial area, and the level of the oil in the wick-holder will not therefore be caused to exceed the bounds set 75 to it, and this excess in the said overflow-chamber must all flow back again into the feed-pipe C and wick-holder B and be consumed before the level of the oil can fall sufficiently low to admit air and renew the 80 supply of oil.

The overflow-chamber D and concentric tube may be so constructed that by raising or lowering them the level of the oil in the wick-holder can be altered, as desired, in order to 85 suit oils of different specific gravities. This arrangement is shown in section at Fig. 4. In this case the supply-pipe C is uncut, and is provided with two or more sets of air-holes f and f' , the outer sliding pipe C^x carrying 90 the overflow-chamber D , and being provided with one set of air-holes only at g at the bottom of the chamber. Upon sliding this outer tube C^x up or down so as to bring the holes g level with either the holes f or f' on the inner or supply pipe c the level of the oil, in the wick-holder will be raised or lowered accordingly. It will be evident that this pneumatic arrangement will be equally applicable to various other purposes, wherein it is 95 desired to maintain a liquid at a constant level.

In the case of portable lamps, whether hand or pillar lamps, the oil-reservoir and the overflow-chamber D will be either placed in 100 or be otherwise attached to the body of the lamp itself; but in the case of permanent fittings (whether suspended or otherwise) the said chamber may be attached to the gasolier-bracket or other fitting; or it may be attached to the supply-pipe, as shown at Fig. 1 or otherwise, so long as it is on the same level as the wick-holder or "burner," and, as before stated, it may be either permanently fixed at that level or it may be adjustable to different levels to suit oils of varying specific gravities. The oil-reservoir must be placed at a higher level.

In all cases provision is made by causing the lower end of the feed-opening to project 110 into the reservoir, as shown at Fig. 1, or by a dome or otherwise to leave a sufficient quantity of air in the reservoir when it is filled.

I claim as my invention—

1. In appliances for burning heavy hydro-carbon oils, the combination of an air-tight pneumatic oil-reservoir and a supply-pipe, with a tube concentric to the supply-pipe, and an overflow-chamber surrounding the supply-pipe at a level with the burner, the said 125 chamber communicating at its lower part with the supply-pipe and having an extended area, all substantially as and for the purpose set forth.

2. In appliances for burning heavy hydro-carbon oils, the combination of an air-tight pneumatic oil-reservoir, a supply-pipe, and a tapering tube, the larger end of which is fitted air-tight within the supply-pipe, the smaller and lower end being on a level with the burner, an air-inlet in the supply between the two ends of the tube, with an overflow-chamber communicating at the base with the supply-pipe, as and for the purpose set forth.

3. In appliances for burning heavy hydro-carbon oils, the combination of an air-tight pneumatic oil-reservoir and supply-pipe, with

an overflow-chamber on a level with the burner, communicating at its base with the supply-pipe and provided with an inlet at the top, and a tapering tube fitted in the supply-pipe, as and for the purposes set forth.

In testimony whereof I have signed my name to this specification in the presence of two subscribing witnesses.

FRAS. M. SIMS.
